UNITED STATES PATENT OFFICE.

ISHMAEL W. MACY, OF GALION, OHIO, ASSIGNOR TO THE GALION IRON WORKS & MFG. CO., OF GALION, OHIO, A CORPORATION OF OHIO.

BUCKET-POSITION-INDICATING MEANS FOR HOISTS.

Application filed May 1, 1928. Serial No. 274,319.

This invention relates to hoisting systems used for hoisting materials from a pit, carrying the hoisting bucket or equivalent element to a bin, discharging the bucket into the bin, and then returning the bucket back to the pit for re-loading, and particularly to means for indicating to the operator the vertical elevation of the bucket at any time and the position of the bucket with relation to the bin and pit so that the operator, by looking at the indicator, can see exactly where the bucket is at any one time and thus operate his control levers in accordance therewith.

Such hoisting mechanism is illustrated, 15 described and claimed in my pending application for patent Serial #274,320 filed on the first day of May, 1928, the hoisting bucket which I design to use with such a system and such winding drum mechanism being disclosed in application Serial #275,477 filed on the fifth day of May, 1928.

The general object of the present invention is to provide indicating mechanism of the character described which includes two indicators, one operated by the hoisting drum and indicating the upward or downward movement of the carrier or elevator bucket or skip, and the other indicating by means of a swinging pointer the position of the bucket with relation to the various bins and being operated by frictional engagement with the traction cable which causes the traverse of the bucket.

A still further object of the present invention is to provide a traverse indicator including a dial and a pointer traveling around the dial and caused to move from a zero position by the movement of the hoisting drum from a position over the pit to a position over the various bins, and specifically to provide means whereby the pointer is disengaged from this driving mechanism upon a return movement of the bucket and particularly upon a return movement of the bucket when 45 the bucket has been lowered to its full extent so that the pointer will automatically return to a zero position, thus causing the pointer to return to a correct zero position at all times without regard to any stretching or 50 lengthening of the cable due to the operation of the hoisting mechanism or expansion or contraction.

A more specific object in this connection is to provide a weighted pointer which is at zero when it is in a vertical position so that 55 when the driving gear for this pointer is released upon the return of the hoisting indicator to its lowermost position, indicating that the bucket has in turn been lowered into the pit to its fully lowered position, the pointer or traverse indicator will swing by gravity to its zero position entirely disconnected from its driving mechanism.

Other objects will appear in the course of the following description.

My invention is illustrated in the accompanying drawings, wherein:

Figure 1 is a fragmentary top plan view of a winding apparatus such as is completely shown in my application for patent Serial 70 #274,320 filed on the first day of May, 1928, and illustrating in plan the indicating means;

Figures 2 and 3 are elevations of the lever and link respectively used for the purpose of disconnecting the traversing drum indicator so as to permit it to swing freely;

Figure 4 is an elevation of the disconnecting lever;

Figure 5 is a section on the line 5—5 of Fig. 1;

Figure 6 is a fragmentary elevation of the upper end of bracket 19;

Figure 7 is a fragmentary section of one end of the hoisting drum and of the indicating mechanism connected thereto;

Figure 8 is a detail fragmentary view partly in section of the lower end of the hoisting drum indicator screw showing the hoisting drum indicator nut and the collar in section;

Figure 9 is a sectional view through the hoisting drum indicator screw and the standard supporting the same showing in top plan the bracket for supporting the indicator screw;

Figure 10 is an elevation of the casing supporting the gearing for the traversing drum indicator looking toward the inside face of the casing;

Figure 11 is a section on the line 11—11 100 of Figure 10;

Figure 12 is a horizontal sectional view of the casing showing the gearing in a plan view.

Referring to the drawings, 10 designates

the base upon which the winding drums are mounted, and 11 designates a shaft mounted upon said base and supporting the drum or spool 12, which I will call the traverse drum, 5 and from which extends the cable 13 which, through mechanism not illustrated, acts to cause the traverse of the hoisting bucket along an overhead track or way and to a position over any desired bin or over a pit 10 into which the hoisting bucket is to be lowered to be refilled. This drum 12 is engaged with this shaft by means of a suitable clutch mechanism, designated generally 14, and the details of which are not illustrated.

15 The hoisting drum is designated 15 and this drum also is provided with clutch mechanism whereby it may be placed in rotative engagement with its shaft or out of such rotative engagement, and both of these drums 20 are provided with brakes adapted to be automatically applied when the clutches are shifted to disconnect one or the other of the drums from the driving shaft therefor. This mechanism is fully illustrated and described 25 in my copending application, Serial #274,320 filed on the first day of May, 1928, and in detail has no connection to the present invention.

Mounted upon the drum 15 to rotate therewith is a beveled gear wheel 16, and disposed upon a pedestal 17 which supports one bearing 18 for the shaft 11 is a bracket 19 which supports at its upper end the angular terminal member 20 which is to support a brake band and which is formed at its lower end with a socket 21 adapted to fit over the upper end of the bracket 19 and be held thereto by a set screw.

40 Mounted below the upper end of the bracket 19 are the collars 22, these collars supporting bearings 23 for a screw-threaded shaft 24. Also mounted upon these collars is an indicator bar 25 having an angularly turned upper end 26 which also constitutes a bearing for the screw or worm 24. This bar is held in place upon the collars 23 by means of the set screws 27. Mounted upon this bar 25 is a scale plate or index plate 28 having altitudes marked thereon, these altitudes indicating the loading position in the pit and ground level and indicating in feet and fractions thereof the distance from the ground level to the uppermost position to which the bucket or skip is to be hoisted.

55 This plate is provided with lugs 29 whereby it may be attached to and engaged with the vertical bar 25. The lower end of the screw or worm 24 carries upon it the beveled gear wheel 30 which engages with the beveled gear wheel 16 so that as this beveled gear wheel 16 which is mounted upon the drum 15 is rotated in one direction or the other, the screw will be rotated in one direction or the other to raise or lower an indicator 31, this

65 indicator 31 having a nut 32 engaged by the screw-thread of the worm 24 and traveling up or down as the screw is rotated. Thus it will be seen that when the bucket is connected to the hoisting cables is hoisted by the winding drum, the indicator will move 70 upward and will indicate on the scale the position of the bucket, whether it is at ground level or at any other desired level above the ground, and that upon a return movement of the bucket the indicator will show the position of the bucket above the ground and also in its lowest position the position of the bucket 75 in the pit where it is to be loaded.

For the purpose of indicating the traverse of the bucket from a position immediately 80 above the pit to a position over any one of the bins (not shown), I mount upon the hoist base 10 to one side of the traversing cable drum 12 a casing 33 which has a supporting bracket 34 formed therewith. Forming part 85 of the case and constituting one face thereof is a circular dial 35 and extending centrally through this dial is the stub shaft 36 which carries upon it a pointer 37 having formed therewith the weight or pendulum 38 which constantly tends to keep this pointer pointing upward at zero upon the dial. The dial is provided with certain indications, as will be later stated, indicating the position of the bucket at various bins.

95 Mounted upon the shaft 36 is a gear wheel 39 disposed within the case 33. Extending through an opening 40 in the case 33 is a short shaft 41 which upon its exterior end carries a friction wheel 42. This wheel, as shown in Figure 3, bears against the cable 13 wound upon the traversing drum 12. In order to urge the wheel yieldingly against the cable, the shaft 41 is carried upon a lever 43. This lever is angular in form and pivoted upon a stub shaft at the intersection of its two arms. A spring 48 engages the lower end of this lever and urges the wheel 42 against the cable 13. The shaft 41 loosely engages the upper end of link 44 whose lower end supports a shaft 44^a which carries a pinion 45 engaging the gear wheel 39. This shaft 44^a also carries a gear wheel 46 which engages a pinion 47 on shaft 41.

105 A spring 49 urges the free end of this link 44 toward gear wheel 39. Thus the friction wheel 42 is urged against the cable 13, while the pinion 45 is urged toward gear wheel 39 and into mesh therewith. Power will thus be transmitted under normal circumstances to wheel 42, pinion 41, the gear wheel 46, pinion 45, gear wheel 39, and pointer 37.

115 So long as the indicator 31 is raised, that is, so long as the hoisting bucket is out of the pit, a rotation of the wheel 42 will cause a rotation of the pointer so that as the hoisting bucket traverses the pointer will move around

the dial indicating the various positions of the hoisting bucket and, as the bucket moves back to a position over the pit and before it has lowered, the wheel 42 will turn in a reverse direction and reverse the direction of movement of the pointer until, when the bucket is directly over the pit, the pointer will come to the position shown in Figure 5.

One of the objects of this invention, as before stated, is to provide means whereby the pointer will correct itself or come to its zero position upon the dial at all times without regard to any lengthening of the cable or any contraction in the cable or any deviation of this nature which would tend to throw the pointer out and cause it to move beyond a zero position when the bucket was over the pit. To this end, I provide means whereby the pointer and its actuating gear wheel 39 shall be entirely disconnected from the driving mechanism consisting of the friction wheel 42 and its connected train of gears, when the bucket has been brought to a position over the pit.

The mechanism for this purpose comprises an angular lever 50 pivoted at 50^a upon a wall of the case 33 and having a depending arm 51 and an arm extending laterally beneath the link 44. This arm 51 of the lever has a laterally projecting pin 52 extending through aperture 40 and engaging beneath the link 44. When the depending arm of the lever 50 is pulled inward, this pin 52 cams against the link 44 and lifts this link, the link turning free upon the shaft 41, and this carries the pinion 45 out of mesh with the gear wheel 39 against the action of the spring 49, thus leaving the gear wheel 39, shaft 36 and the pointer free to swing, and then the weight 38 of the pointer will act through gravity to bring the pointer back to a vertical position, which is its zero position upon the dial.

This disconnecting operation of the lever 50 is accomplished automatically by connecting the lower end of the lever 50 by means of a chain, cable or other flexible connection 53 to the indicator 31 which, as before stated, has screw-threaded engagement with the indicator screw. As illustrated, this cable 53 passes downward through right angularly disposed sheaves 54, then passes upward through a guide sheave 55 and over a sheave 56 mounted upon the indicator supporting bar and then to a sliding collar 57 slidingly surrounding the indicator screw 24.

While I have illustrated a particular arrangement of this cable and of the sheaves supporting the same, I do not wish to be limited to this arrangement nor to the provision of a cable for this purpose as other means for connecting the collar 57 to the lever 50 and other means than this chain 53 might be used for this purpose.

When the indicator 31 moves upward on the screw 34, the collar is free to move upward, thus permitting the arm 51 of lever 50 to be swung downward by the contraction of the spring 49. When, however, the nut 32 nearly reaches its lowermost position on the indicator screw 34, it will engage the collar 57 and force this collar down to the position shown in Figure 5 and cause the lever 50 to swing to the left in Figure 10 as heretofore described and secure disengagement between the pinion 44 and the gear wheel 39, permitting, as before remarked, the pointer to swing freely.

It will be seen from Figure 3 that the friction wheel 42 contacts with a plurality of strands of cable on the drum 12. It will be understood that this cable, as is common in traversing drums, loosely surrounds the drum and that both ends of the cable pass off the drum and are connected to the carriage which supports the bucket so that when the drum is turned in one direction the carriage will be drawn toward the drum and when it is turned in the other direction, the carriage will be drawn or traversed away from the drum. Since the cable is not fixed to the drum but is simply moved by frictional contact therewith due to the wrapping of the cable around the drum, it will be readily seen that the drum on a sudden application of the clutch or load may spin inside the cable wrapped around it. There is thus no fixed relation between the drum and the cable as there is in the case of a hoisting drum where the cable is dead ended to the drum and the relation of the cable to the drum always remains constant. If the friction wheel 42 of the traversing indicator bore directly against the traction drum 12, the drum might move inside the cable without the cable moving a corresponding amount. The indicator would then be thrown out of time with the cable. It is immaterial how many revolutions per minute or how many given number of feet of travel the traversing drum makes, but it is of importance to learn the travel of the cable and for this reason, I take the travel indication from the cable itself and not from the drum.

By placing the friction wheel 42 directly opposite the drum, the friction wheel bears against the cable, so that a flat friction wheel may be used which is not affected by the fact that the cable, as the drum rotates in one direction or the other, shifts axially with reference to the drum. By causing the friction wheel to bear against the cable where it winds upon the drum, it is not necessary to arrange for any axial movement of the wheel as it can remain in one position with relation to the traversing drum and any shift of the cables relative to the surface of the drum is taken care of by the relatively wide surface of the

friction wheel which is always in contact with one or more of the three or four strands of cable wrapped around the traction drum.

The indicating means which I have described discloses to the operator the exact position at all times of the bucket. If the bucket is in the pit, that is, in loading position or the position which it would occupy under normal circumstances of non-use, the 10 pointer of the traverse indicator will be at zero and the pointer of the elevation indicator or hoist indicator will be also in its lowest position at zero. When power is applied to the hoisting drum to lift the bucket out of the pit and carry it up into position to be traversed across the bins, the screw 24 will be rotated, causing the indicator to move upward upon the screw. When this indicator reaches a proper elevation, the operator in charge will understand that the bucket has been raised sufficiently to clear the bins and then, by mechanism which forms part of my pending application Serial #274,320 previously referred to, the hoisting drum will 20 be thrown out of action and the traversing drum 12 will be thrown into action, causing, through mechanism not shown and not pertinent to this invention, the traversing of the bucket or other hoisting means over the various bins.

As soon as the hoist commences to traverse across the bins in a horizontal plane, that is, as soon as the traversing drum is operated, the traverse indicator will operate and the 30 pointer 37 will commence to swing around upon the dial. The dial will be provided at intervals with adjustable station indications, designated generally 37^a, and the operator watching the pointer will note just where the hoisting bucket is at any time. The station indicators, as they are adjustable, may be changed to suit any particular arrangement of bins and any particular spacing of bins. This is necessary in view of the fact 40 that no two plants have the bins necessarily spaced the same distances apart. As soon as it reaches a point above the proper bin which is indicated by the pointer, he disconnects the traversing mechanism and operates the hoisting drum so as to lower the bucket into the bin and cause the discharge of the contents. The bucket is then raised to its former level, which is indicated by the indicator screw and the traveling nut thereon, and when the 50 bucket has been hoisted from the bin it is then re-traversed to its position over the pit, usually indicated on the dial 35 by an index letter P.

The traversing mechanism is then thrown 60 out of operation and the hoisting mechanism again operated to lower the bucket vertically downward into the pit, and when the bucket has been fully lowered, the indicator pointer 31, or rather the nut 32, will come in contact 65 with the collar 57, as before stated, auto-

matically acting to disconnect the driving means for the traversing mechanism from the pointer 37 thereof, allowing the pointer to swing to a zero position. Thus it will be seen that this pointer at every trip corrects itself 70 automatically so that it is always at a zero position when the bucket has been fully lowered without regard to any contraction or expansion of the cable, wear of the parts or anything of this character. 75

I claim:—

1. In material handling mechanism, a traversing drum, a cable thereon adapted to cause the horizontal traverse of an article, means for indicating the position of the article being traversed including a dial constituting a scale, a pointer movable around the dial, and means for operating the pointer including a friction wheel engaging the cable on the drum and yieldingly urged toward the 80 cable.

2. In article handling mechanism, a traversing drum, a cable thereon, means for indicating the horizontal position of the article being traversed comprising a scale, an indicator movable over the scale, and means for moving the indicator including a friction wheel engaging the cable on the drum and yieldingly urged toward said cable. 90

3. In material handling mechanism, a 95 drum, a cable wound thereon, and an indicator including a friction wheel yieldingly urged against a portion of said cable which is wound on the drum.

4. In material handling mechanism, a 100 winding drum, an indicator including a freely swinging pointer urged to a zero position, means for operatively connecting the pointer to the drum to move therewith, and means for disconnecting the pointer from the drum to 105 permit the pointer to swing freely to a zero position.

5. In material handling mechanism, a drum having a cable thereon, means for indicating the position in space of the article 110 being shifted by the cable comprising a circular dial, a pointer rotating on an axis concentric to said dial, a series of station indicators mounted upon the perimeter of the dial and adapted to be adjusted to different positions 115 on the perimeter, and means operated by the drum whereby to rotate the pointer.

6. In article handling mechanism, a hoisting drum, a traversing drum, both of said drums having cables whereby an article may 120 be hoisted or traversed horizontally, means indicating the vertical position of the article as it is raised or lowered by the hoisting drum, means indicating the horizontal position of the article as it is shifted horizontally through 125 space by the traversing drum, and means actuated by a return of the indicating means for the hoisting drum to a position indicating the lowest position of the hoisting drum acting to cause the indicator of the traversing drum to 130

return to a zero position independently of the position of the traversing drum.

7. In handling mechanism, a hoisting drum, a traversing drum, both of said drums having cables whereby an article may be hoisted or traversed, means for applying power to either one of said drums or disconnecting either one of said drums, an indicator mounted in connection with the hoisting drum and indicating the vertical position of an article being hoisted, an indicator associated with the traversing drum and operated thereby and indicating the position of the article as it is traversed, means urging the indicator of the traversing drum to a zero position, and means actuated by the arrival of the indicator of the hoisting drum at a predetermined point acting to release the operative connection between the traversing drum indicator and the drum whereby to permit the traversing drum indicator to return to its zero position independently of any movement of the traversing drum.

8. In handling mechanism, a winding drum, a cable thereon whereby an article may be handled by the drum, means for indicating the position of the article in space as the drum is operated including an indicator urged by gravity to a zero position, driving means for the indicator operatively engaging the drum and acting as the drum is rotated to shift the indicator, and means acting automatically when the article has reached a predetermined point to disconnect the indicating means from the driving means therefor to permit the indicator to return to a zero position under the action of gravity independently of any movement of the winding drum.

9. In material handling mechanism, a winding drum having a cable thereon, means for indicating the position in space of an article carried by the cable including a dial, a pointer swinging concentric to the dial and urged to a zero position, pointer operating means normally operating the pointer in consonance with the movement of the drum, and means whereby the pointer may be disconnected from its operating mechanism and permitted to swing to a zero position by gravity.

10. Article handling mechanism including a drum, a cable thereon, an indicator pointer urged to a zero position and having a gear wheel, a driving wheel driven in consonance with the movement of the drum, a toothed wheel urged into meshing engagement with the pointer gear wheel, a member supporting the toothed wheel for movement toward or from the pointer gear wheel, operative connections between the driving wheel and the toothed wheel, and a lever engaging the member and when shifted in one direction disengaging the toothed wheel from the pointer gear wheel.

11. Article handling apparatus including

a drum, a cable thereon, an indicator pointer urged to a zero position and having a gear wheel, a friction wheel adapted to bear against the cable and moving in consonance therewith, a lever upon which the friction wheel is mounted, a spring urging the lever in a direction to carry the friction wheel against the cable, a toothed wheel urged into meshing engagement with the pointer gear wheel, a link loosely mounted upon the shaft of the friction wheel and supporting said toothed wheel for movement toward or from the pointer gear wheel, operative driving connections between the shaft of the friction wheel and the toothed wheel, and a lever engaging said link and when shifted in one direction disengaging the toothed wheel from the pointer gear wheel.

12. An indicator mechanism for winding drums including a dial, a weighted pointer movable over the dial and urged by gravity to a zero position, a gear wheel connected to the pointer to move the same, a lever, a shaft carried by the lever and carrying a driving wheel, a spring urging the lever in one direction, a pinion carried upon said shaft, a link loosely mounted upon the shaft and carrying a shaft at its free end, a gear wheel mounted upon said last named shaft and engaging the first named pinion, a pinion mounted upon the last named shaft engaging the pointer gear wheel, a spring urging the link in the direction to carry the last named pinion into meshing engagement with the pointer gear wheel, and shiftable means for shifting said link to shift the last named pinion out of engagement with the motor gear wheel.

13. In article handling apparatus, a hoisting drum and a traversing drum, a cable on the traversing drum, a member movable by and with the hoisting drum and moving in consonance with the article being hoisted by the drum, an indicator for the traversing drum including a dial, an indicator pointer movable over the dial and urged by gravity to a zero position, a friction driving wheel having a shaft, a spring retracted lever supporting said shaft, a link loosely mounted upon the shaft, a pinion carried upon the shaft beyond the link, a gear wheel mounted upon the link and engaging said pinion, the center of the gear wheel and the rotative center of said lever being coincident, a pinion coaxial with and rotating with the last named gear wheel, a shaft upon which the pointer is mounted and having a gear wheel with which said last named pinion engages, a spring urging the link in a direction to cause the meshing of the last named pinion and the pointer gear wheel and indicator for the hoisting drum and having a vertically movable traveler, a lever engaging at one end beneath the link, and means actuated by the traveler when it arrives in a predetermined position shifting

said levers to shift the link to thereby disengage the last named pinion from the pointer gear wheel and permit the pointer to freely swing to a normal position.

5 14. In a material handling mechanism, a drum, a cable having several coils extending around the drum, and an indicator including

a friction wheel yieldingly urged against said coils on the drum and having a relatively wide surface equal to the width of a plurality of coils. 10

In testimony whereof I affix my signature.

ISHMAEL W. MACY.
